UNITED STATES PATENT OFFICE.

ROSCOE D. CONKLIN, OF RAHWAY, NEW JERSEY, ASSIGNOR TO NATIONAL PNEUMATIC COMPANY, OF NEW YORK, N. Y., A CORPORATION OF WEST VIRGINIA.

AIR COMPRESSOR.

Application filed December 23, 1924. Serial No. 757,582.

This invention relates to air compressors for gasoline motors and has for its object the production of a construction which is operated directly from the explosive impulses produced in the cylinder to which it is attached and whereby air is compressed for any purpose at hand, as the operation of doors on motor buses, the operation of brakes, or for any other purpose for which compressed air is used.

A further object includes the provision of a single construction for the purpose stated, which is readily attached to the cylinder head of an internal combustion engine to be operated thereby for compressing air.

Other objects will appear hereinafter, and I attain these objects by the construction illustrated in the accompanying drawings in which

20 Fig. 1 is a side view of a device embodying the principles of my invention.

Fig. 2 is a view taken on line 2—2 of Fig. 1 showing the device applied to a cylinder head, and

25 Fig. 3 is a plan view thereof.

Like numerals refer to similar parts throughout the several views.

It is among the prime objects of my invention to provide ready means whereby an ample supply of compressed air is always at hand for the operation of accessories on motor buses or motor driven vehicles, and for any device where compressed air is used.

To provide a constantly available supply of compressed air, I utilize a small proportion of the explosive impulses of the operating motor cylinder for the purpose of operating the air compressor unit 10, which is tapped into the head of a cylinder 11, and secured

40 by a screw tap 12, or the like. As illustrated in my preferred construction, to which I do not, however, desire to be limited, the compressor unit comprises a main cylinder 13 having heat radiating fins 14, a double head

45 piston 15, and a valve containing head 16. While I have shown a single unit attached to the head of a piston in a longitudinal position, it is obvious that the said unit may be vertically attached and that any number of units may be used depending upon the requirement of the air supply.

In the construction illustrated, the double headed piston 15 has compression piston 17 spaced apart from the impulse piston 18 by a stem on which is fitted an expansion spring

19 which is attached to locating devices or screws 20. Both pistons are provided with suitable packing rings 21, 21. A shock absorbing ring 22 of suitable material as asbestos softens the shock of the impulse piston 18 and another asbestos pad 23 similarly guards the compressor piston 17. The valve head 16 contains an intake valve 24 for admitting air from the outside, a compressor valve 25 and connection nipple 26. The intake valve includes a tubule 27, a valve ball 28 and a valve spring 29, all arranged to admit air through valve 24 into compressor space 30 above the compressor piston 17. The compressor valve includes an adjustable plug 31 having a lock nut 32, a ball spring 33 for positioning the valve ball 34 on its valve seat 35. An outlet or safety vent 36 in the wall of the cylinder 13 provides for pressure release within the spring chamber of the cylinder.

From the disclosure thus far given, the operation of my air compressor is self-evident. Normally the tension of spring 19 holds the pistons in the position shown in Fig. 2; that is in depending position. An explosive impulse in cylinder 11 causes the double headed cylinder 15 to be moved against the compression spring 19 and thereby expel air from the compressor cylinder space 30 through valve 34 and nipple 26 and into the compression tank (not shown). This action is but momentary, and the moment that the pressure in cylinder 11 falls, the double headed piston will resume its normal position and in so doing will cause air to be taken into chamber 30 through the intake valve 24 for the next compression charge when the explosive impulse again occurs in cylinder 11.

While I have shown but a single compressor unit attached to a single engine cylinder head, it is evident that more than one unit may be utilized to compress air at the desired rate, and that these units may be located in the most effective manner on the same or on different cylinders. In case it is desired to stop the operation of the compressor unit, the double headed piston is then locked in any suitable manner as by a properly controlled catch 37 engaging a detent 38 in the compressor piston 17 to hold the same in position.

It will be seen from the foregoing that I have provided an air compressor which does

not employ the exhaust gases of the engine. In other words, the only air that is compressed and stored is the fresh, outside air, and hence all the disadvantages and troubles incident to the attempt to employ impure, gas laden or exploded gas fluid, are eliminated.

Having now described my invention, what I claim as new and useful, of my own invention and desire to secure by Letters Patent is:

1. In an air compressor, a single cylinder, a double headed piston member in said cylinder, means mounted between the heads of said member for tensioning said double headed piston in one direction, and means for alternately opening and closing one end of said cylinder to the atmospheric air.

2. An air compressor for internal combustion

engines, comprising a single cylinder having a valved head to close one end of said cylinder, and having the other end open to propulsive influences in the operating motor cylinder, a reciprocating member having heads of equal diameters in said cylinder positioned to be moved by the said propulsive influences to thereby cause air to be compressed by said reciprocating member, a spring mounted between said heads and lugs projecting into the cylinder, said spring resting at one end on one of said heads and at the other on said lugs.

In testimony whereof I have hereunto set my hand on this 19th day of December, A. D., 1924.

ROSCOE D. CONKLIN.
